UNITED STATES PATENT OFFICE.

EDGAR A. TINSMAN, OF AKRON, OHIO, ASSIGNOR TO THE STANDARD TIRE CO., OF WILLOUGHBY, OHIO, A CORPORATION OF OHIO.

DESIGN FOR A VEHICLE-TIRE.

53,949.

Specification for Design.

Patented Oct. 7, 1919.

Application filed June 12, 1919. Serial No. 303,795. Term of patent 14 years.

To all whom it may concern:

Be it known that I, EDGAR A. TINSMAN, a citizen of the United States, residing at Akron, in the county of Summit and State of Ohio, have invented a new, original, and ornamental Design for a Vehicle-Tire, of which the following is a specification, reference being had to the accompanying drawing, forming part thereof.

Figure 1 is a side view, Fig. 2 a plan view, and Fig. 3 a cross section showing my new design for a vehicle tire.

I claim:

The ornamental design for a vehicle tire, as shown.

EDGAR A. TINSMAN.
